MUSICAL INSTRUMENT

Joseph Gaukstern, Maplewood, N. J., assignor to
Chris Kratt Company, Union, N. J.

Application March 27, 1946, Serial No. 657,460

4 Claims. (Cl. 84—377)

1

My invention relates to musical instruments, more particularly to reed instruments played by the breath.

In a conventional device referred to as a harmonica, an elongated flat tooth-like member referred to as a comb has attached to opposite faces reed plates, usually of metal, supporting a plurality of reeds which are positioned and supported in registry with elongated apertures or slots in the plates. These slots and reeds register with the spaces between the teeth of the comb member. These plates are usually nailed or stapled to the flat elongated comb. Positioned over the plates to protect the reeds and provide a smooth exterior are cover plates, likewise nailed or stapled to the comb. The comb is usually of hard wood. The reeds themselves are usually thin elongated metal ribbons secured to the plate by means of separate rivets so as to lie adjacent the slots and in registry therewith.

In assembly the comb and the reed plates are more or less aligned by eye, the nails extend through the reed plates into the comb. The cover plates are then also nailed to the comb. In fixing the reed plates and cover plates alignment can be and is frequently affected and the nails or staples are not always as tight as they should be. This permits the reed plates under certain conditions to vibrate along with the reeds causing impure tones and lack of resonance. Lack of tightness also causes loss of air, thereby increasing the energy required for operating the instrument and causing inferior quality of tone. In time nails or staples become loose, not only due to use but also due to the fact that the wood of the comb, because of absorbed moisture, alternately swells and contracts. This may permit shifting of the reed plates and contact between reeds and the comb teeth, thus destroying the value of the instrument.

Another objectionable feature to the use of wood combs is that it is extremely difficult to make one comb the exact duplicate of another. This requires more adjustments in assembly and increases the time of assembly which is required. The alternate swelling and contraction of the wood, due to absorption of moisture, may also be the cause of cracks in the wood, thereby affecting clarity of tones and resonance, and rendering the instrument to be in most cases unplayable.

It is customary to make the comb in such a way that the longitudinal axis coincides with the grain of the wood, the teeth being cut across the grain. As a result it is difficult to round the ends of the teeth of the comb, the resulting sharp

2

edges causing irritation of the lips and tongue of the player.

With the usual nailed construction it is impossible to either clean or repair the instrument or to tighten up the parts once they become loose, because removing the nails or staples damages the instrument beyond repair as a rule.

It is, therefore, an object of my invention to provide an improved musical instrument of the reed type which is played by the breath.

Another object of my invention is to provide such an instrument which may be quickly, accurately and automatically lined up, thereby increasing production and insuring a more accurate construction.

Another object of my invention is to provide an instrument which is air-tight and in which the various elements are firmly and tightly secured together as a compact unit.

20 Another object of my invention is to provide a comb of a construction and material which eliminates absorption of moisture, loosening of the parts and cracking and which can be accurately made and duplicated.

25 A still further object of my invention is to provide such an instrument which may be disassembled for cleaning and which can be easily repaired or tightened.

These and other objects will appear hereinafter.

The novel features which I believe to be characteristic of my invention are set forth with particularity in the appended claims, but the invention itself will best be understood by reference to the following description taken in connection with the accompanying drawing in which Figure 1 is a plan view with parts broken away to show details of construction, Figure 2 is a section taken along the line 2—2 of Figure 1, Figure 3 is an exploded view in perspective showing details of construction and method of assembly, Figure 4 is a plan of a detail showing the reed plate and reed, and Figure 5 is a section taken along the line 5—5 of Figure 4.

30 In accordance with my invention I provide an elongated flat comb member 10 having a plurality of teeth 11, 12 and 13 rounded as indicated. This comb plate is provided with a pair of shoulders 14 and 15 extending along one longitudinal edge for purposes to be described. I preferably mould

35 this comb element of some plastic material, thus insuring accurate and like pieces under all conditions. The molded comb is not subject to splitting, will not absorb moisture and thus will not contract and expand under playing conditions and loosen the parts of the instruments.

Because of the rounded teeth, no irritation is caused by contact of the tongue or lips with the teeth on the comb.

It is highly desirable that the reed plates should be tight against a surface of the comb and that no air escape during playing except by the reeds. The reed plates 16 and 17 are secured to opposite faces of the comb 10 by means of the screws and nuts 18, 19 and 20. They are assembled by inserting the reed plates and comb plate in a fixture, the reed plates being slightly wider than the comb so that pressure may be exerted against the free edges to push the plates against the shoulders 14 and 15. The screws and nuts are then positioned in place and the plates tightened down against the comb by drawing up the screws and nuts. This not only tightens the plates against the opposite faces of the comb, but also places the edges tightly against the shoulders 14 and 15 to further insure a mechanically tight and air-tight assembly. This prevents shifting of the reed plates and binds the reed plates and comb solidly into one compact body which improves the tone as to clearness and volume. As pointed out above, the shoulders serve to establish a close contact with the reed plates and thereby act to prevent escape of air which reduces the consumption of air while playing the instrument and improves the tone besides making the instrument easy to play. The shoulders further serve to bind the reed plates and comb element into one solid, tight body. The shoulder also permits uniform and accurate assembly of the elements of the instrument as the shoulders serve as an end base for the reed plates. The cover plates 21 and 22 may then be positioned over the reed plates and secured to the comb and reed plates by nuts and screws such as 25 and 26 passing through the cover plates, reed plates and comb.

Because of the fact that the elements are bolted together, they may easily be taken apart for cleaning and repairing or may be easily tightened without any harm or damage to any component parts. This prolongs the life and quality of the instrument.

In accordance with my invention the reed plates are provided with a plurality of slots, such as 30 shown in Figure 5, with which the reed element, such as 31, registers. The reed 31 is provided with a square head 32, which is apertured. The reed plate 16 is provided with an extruded portion 33 which is received within the aperture within the head 32 of the reed. The extrusion is then peened over as at 45. In this way an extra element is saved and an extra operation of inserting a rivet through the aperture in the reed plate and the reed is also eliminated. If desired the extruded portion could be made square as well as the aperture in the reed so that the reeds are automatically and accurately positioned when received over the extrusion.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. A reed instrument including a molded

elongated plate-like comb element of plastic material and having along one edge shoulders having inside shoulders normal to the surface of said plate-like comb element, and a plurality of teeth along the other edge, reed plates coextensive with said comb element and each having one longitudinal edge in engagement with an inside surface of a shoulder, the other longitudinal edge of each of said reed plates extending slightly beyond the ends of the teeth of said comb element, said comb element and said reed plates having registering apertures extending therethrough adjacent said shoulder and screw means for maintaining said reed plates and said comb element in engagement, and cover plates extending coextensive with said comb element and said reed plates, the ends of said comb element, reed plates and cover plates having registering apertures extending therethrough, and screw means bolting said reed plates, cover plates and comb element compactly and tightly together, said reed plates having reeds registering with the spaces between said teeth, said plates having integral extruded portions extending through the reeds and peened over against said reeds to secure said reeds to said plates, said teeth being rounded at their outer ends, said reed plates permitting pressure to be applied to said other longitudinal edges upon assembly of said instrument whereby said screw means can be tightened to lock the elements of said instrument in aligned and tight assembly.

2. A reed instrument including a molded elongated plate-like comb element of plastic material having along one edge shoulders having inside surfaces normal to the surfaces of the plate-like comb element, and a plurality of teeth along the other edge, the ends of said teeth on said comb element being rounded, reed plates coextensive with said comb element and each having one longitudinal edge in engagement with an inside surface of a shoulder, the other longitudinal edge of said reed plates extending slightly beyond the ends of the teeth of said comb element, said comb element and said reed plates having registering apertures extending therethrough adjacent said shoulders, and screw means for maintaining said reed plates and said comb element in engagement, cover plates extending coextensive with said comb element and said reed plates, the ends of said comb element, reed plates and cover plates having registering apertures therethrough, said reed plates permitting pressure to be applied to the other longitudinal edges upon assembly of said instrument whereby said screw means may be extended through said registering apertures for bolting said reed plates, cover plates and comb element in aligned and tight assembly.

3. A musical instrument including a molded, elongated, plate-like element of plastic material and having a plurality of teeth along one edge and shoulders having inside surfaces normal to the opposite faces of said plate-like comb element at its opposite edge, a reed plate coextensive with each face of said comb element and having one longitudinal edge in engagement with an inside surface of a shoulder, the other longitudinal edge of said reed plates extending slightly beyond the ends of the teeth of said comb element and means clamping said reed plates against said shoulders and the faces of said comb element, the ends of said teeth of said comb element being rounded, said reed plates permitting pressure to be applied to said other longitudinal edges upon assembly of said instrument whereby

said clamping means can be locked in place with the elements of said instrument in an aligned and tight assembly.

4. A musical reed instrument including a molded, elongated, plate-like comb element of plastic material having along one edge shoulders having inside surfaces extending from opposite faces of and normal to the faces of said plate-like comb element, a reed plate on each face of said comb element and coextensive of said comb element and having one longitudinal edge in engagement with the inside surface of an adjacent shoulder and means clamping said reed plate against the face of said comb element, the thickness of said reed plate and the height of 15 said shoulder being substantially the same whereby said shoulder and the surface of said reed plate are flush with each other, the other edge of said reed plate extending slightly beyond the ends of the teeth of said comb element, the 20 ends of said teeth being rounded, said reed plates permitting pressure to be applied to said other edges upon assembly of said instrument whereby said clamping means can be locked in place with the elements of said instrument in an aligned 25 and tight assembly.
